UNITED STATES PATENT OFFICE.

ADOLPH H. COHN, OF NEW YORK, N. Y.

GARMENT-CLASP.

SPECIFICATION forming part of Letters Patent No. 718,814, dated January 13, 1903.

Application filed April 17, 1902. Serial No. 103,397. (No model.)

To all whom it may concern:

Be it known that I, ADOLPH H. COHN, a citizen of the United States, residing at New York, in the county of New York and State of New York, have invented certain new and useful Improvements in Garment-Clasps; and I do hereby declare the following to be a full, clear, and exact description of the invention, such as will enable others skilled in the art to which it appertains to make and use the same.

My invention relates to certain improvements in garment-clasps, and has for its object to provide a simple and economical device of this description which can be readily manipulated.

In the accompanying drawings, which form a part of this application, Figure 1 is a perspective view illustrating my improved form of clasp; and Fig. 2 is a plan of the form of loop which I employ.

Similar numbers of reference denote like parts in both figures of the drawings.

My invention has particular reference to that style of clasps which comprise a button and a slotted plate, commonly called a "loop," the latter being usually made with a slot large at the top, so as to admit the head of the button, and small at the bottom, and the chief aim of my invention is to do away with the necessity of providing for the reception of the head of the button.

1 is the button, whose base-plate 2 is secured to the usual webbing 3, and 4 is a sheet-metal plate secured to a webbing 5. Within this plate 4 is an elongated slot 6, of uniform width throughout its length, and at one side of the plate, near the upper end of said slot, is a gate 7, which leads into said slot and is of a width substantially the same as the width 40 of the slot. The slot 6 and gate 7 are of a width slightly greater than the diameter of the shank of the button, so that such shank may readily and freely pass through said slot and gate.

45 In utilizing my improvement the garment is placed over the head of the button and the shank of the latter pushed through the gate 7 and then drawn down to the bottom of the slot 6.

50 The button may be of plain metal or it may

be made of rubber, or the shank of the button may be provided with a rubber collar, and my invention is therefore not limited in this respect. It will thus be seen that the head of the button never passes through the slot or 55 the gate, and therefore a very broad head may be employed, if desired, such as would have a substantial bearing upon the face of the plate when the shank is drawn down to the bottom of the slot.

Having thus described my invention, what I claim as new, and desire to secure by Letters Patent, is—

1. In a garment-clasp, the combination of the button having a base-plate secured to a 65 flexible element, with the loop having its upper end also secured to said flexible element immediately above said button, said loop having a slot of uniform width in the direction of its length and a lateral gate opening into 70 said slot, whereby the fabric to be sustained may be placed over the head of the button and the shank of the latter forced through said gate into said slot and then drawn down to the bottom of the latter, substantially as 75 set forth.

2. In a garment-clasp, the combination of the base-plate secured to a piece of webbing, said plate having rising therefrom a shank which terminates in a large head, with a second plate having its upper end secured to said piece of webbing and provided with an elongated slot of uniform width slightly greater than the diameter of said shank, said slot extending lengthwise of said second plate, 85 the latter being also provided with a lateral gate having a width equal to that of said slot and opening into the latter near the upper end thereof, whereby said shank with the fabric to be sustained around the same may 90 be forced through said gate and drawn downwardly to the bottom of said slot, substantially as set forth.

In testimony whereof I affix my signature in presence of two witnesses.

ADOLPH H. COHN.
